UNITED STATES PATENT OFFICE.

JOHN C. GRAHAM, OF PHILADELPHIA, PENNSYLVANIA.

DESIGN FOR GIMP.

SPECIFICATION forming part of Design No. 16,091, dated May 19, 1885.

Application filed March 17, 1885. Term of patent 14 years.

To all whom it may concern:

Be it known that I, JOHN C. GRAHAM, a citizen of the United States, residing in the city and county of Philadelphia, in the State of Pennsylvania, have invented a new and original Design for Gimp, of which the following is a specification.

My design for gimp is fully illustrated in and by the accompanying drawings, in which—
10 Figure 1 is a face view of a strip of gimp embodying my design, and Fig. 2 a detailed face view of one of the principal ornamental figures of the design.

The gimp itself may be of any preferred width and of any material and coloring.

In the drawings, A represents the body of the gimp, longitudinally throughout which runs a broad central band, B. This band contrasts in color with the color of the body of the gimp. The degree of contrast, however, is not material. Transversely across the band, and vertically with respect to the body of the gimp, are placed in succession a series of Z-shaped ornaments, C, which are represented in detail in Fig. 2, and which may be described as consisting of a central body, and of a head and tail piece, c c', which respectively stand at an acute angle with regard to the body. These ornaments are arranged at uniform intervals throughout the length of the gimp,

and are of sufficient extent to, as to their head and tail pieces, overlap the band, as shown. The edges of the gimp may be scalloped in the usual manner, and as represented in the drawings.

35

The ornaments C are of lighter color than the coloring of the body of the gimp and of the band. Irrespective, however, of the colors which I employ, I claim—

1. A design for gimp, consisting of a body, 40 A, and of a series of corresponding Z-shaped ornaments, C, substantially as shown and described.

2. A design for gimp, consisting of a body, A, a longitudinally-extending band, B, and a 45 series of Z-shaped ornaments, C, substantially as shown and described.

3. A design for gimp, consisting of a body, A, and of a series of successively and uniformly disposed ornaments, C, the ends of 50 which ornaments occupy an acute angle with respect to their body, substantially as shown and described.

In testimony whereof I have hereunto signed my name this 3d day of March, A. D. 1885.

JOHN C. GRAHAM.

In presence of—

WM. C. STRAWBRIDGE,
J. BONSALL TAYLOR.
